POWER CONVERTING UNIT AND SYSTEM

Jerome Nathan Stowell, Fargo, N. Dak.

Application May 10, 1933, Serial No. 670,384
Renewed March 16, 1935

5 Claims. (Cl. 176—124)

This invention relates to power converting units and systems and aims generally to provide an improved unit and system of this character which, in one illustrative application thereof, will 5 be capable of transforming a low potential input current to produce output current at high potential and of such character as to be capable of smoothly operating a neon-gas tube or the like without flicker, and uniformly throughout its 10 length for all practical purposes, and with very small drain upon the source of primary current. In a preferred embodiment exemplifying the capabilities of my improved system in this illustrative application thereof, the system may be 15 devised to produce a current output, at 17,500 volts, capable of thus operating a neon-gas tube seventy (70) feet in length, while drawing a current of less than two (2) amperes from a six (6) volt storage battery.

Attempts have heretofore been made to operate neon-gas tubes or the like from low voltage sources of direct current by employing an induction coil to produce therefrom a high voltage current for illuminating the tube, but such systems have been found not entirely satisfactory 20 for at least two reasons; first, because of the characteristic flicker obtained, and second, because of the inherent character of the current output of induction coils in general, which renders a neon-tube supplied with current thereby brilliant at one end and dimmer at the other.

The system of my invention, however, overcomes the above mentioned disadvantages of the usual induction coil systems, without the employment 25 of complicated mechanism, and at the same time effects a considerable saving in current consumption as compared with the induction coil systems heretofore used, as hereinafter shown.

The accompanying circuit diagram is illustrative of a preferred embodiment of my improved system as applied to the operation of a neon-gas tube sign.

In this preferred embodiment of my invention a source of power 10 is indicated conventionally 30 and may be an ordinary six volt storage battery with positive and negative terminals as indicated.

The converter embodying my invention in this illustrative arrangement comprises a transformer, herein consisting of the primary 11, the 35 soft iron core 12 which advantageously may be of the closed type and of laminated or other usual construction, and the secondary 13, in suitable ratio to the primary 11.

Arranged in parallel with the primary 11 of the 40 transformer is an electromagnet separate and

apart therefrom, herein embodying the coil 14 and the soft iron core 15 of laminated or other suitable construction, which functions, with the contact means hereinafter described, to rapidly and repeatedly interrupt the current supplied to the parallel system comprising the coils 11 and 14. The contact means aforesaid may be of any suitable construction, but in the form shown comprises a stationary contact 16, which may be adjustable, and a vibratory contact 17, herein carried by a paramagnetic spring-arm 18 mounted rigidly or adjustably upon any suitable support 19, and positioned to be drawn away from the contact 16 by magnetic flux generated by the electromagnet 14, 15. The parallel system comprising the coils 11 and 14, proportioned so that in operation the major portion of the current passes through the coil 11 and the minor portion through the coil 14, is arranged in series with the contact means 16, 17, and with the source of 20 power 10, as shown, and the contact means 16, 17 is bridged or arranged in parallel with a heavy non-electrolytic condenser 20. With this arrangement and proper adjustment of the proximity to the electromagnet of the contacts 16, 17 25 and of the tension of the spring-arm 18, the supply of current to the parallel system 11 and 14 of the converter will be rapidly and repeatedly broken and remade by the effect of energization and deenergization of the electromagnets 14, 15. 30

In practice I find that this arrangement,—in which I follow the novel method of drawing current from a low voltage source, dividing it into two portions flowing in parallel, employing one of said portions to energize an electromagnet, the 35 magnetic flux of which is applied to operate means for rapidly and repeatedly interrupting the entire current drawn from the source, employing the other portion in parallel with the first to energize the primary of a transformer, 40 and utilizing the magnetic flux developed by the current in the primary of the transformer solely for operation of the step-up transformer;—produces from such low potential source of current, a current output of high voltage and of an alternating character with the opposite sides of its cycle sufficiently equal to illuminate a lamp of the neon-gas tube type with uniform brilliance throughout its length so far as is readily perceptible by the eye, and without objectionable 45 flicker.

In actual practice I have successfully achieved the results desired, employing the arrangement herein disclosed to illustrate my invention to operate a neon-gas tube seventy (70) feet in 50 55

length, without perceptible flicker or noticeable inequality of illuminating, with the output potential at 17,500 volts, from a six (6) volt storage battery with a current drain thereon of less than two (2) amperes. In this installation I have employed a non-electrolytic condenser 20 having a capacity of about 1.5 microfarads, and capable of withstanding a potential of 50 volts, a transformer having a primary winding of about 10 400 turns of number 18 wire (standard gauge) and a secondary winding of about 17,500 turns of number 36 wire (standard gauge) with an electromagnet 14, 15 having about 400 turns of number 16 wire (standard gauge), the rate of 15 interruption of the circuit by the electromagnetic interrupter 14—19 being adjusted, by adjustment of the contacts and tension of the spring 18, as aforesaid, to attain the desired 20 character of current output, which, as a general rule, will be about 200 cycles or 400 interruptions per second.

In another installation for operating a shorter neon-gas tube, I have obtained equally satisfactory results with an output potential of 7,500 25 volts, and input from the six (6) volt storage battery, utilizing a non-electrolytic condenser of 1.5 microfarads capacity, and capable of withstanding a potential of 50 volts, with the transformer primary consisting of 350 turns of number 30 18 wire (standard gauge), the secondary of 7,500 turns of number 36 wire (standard gauge), and the electromagnet coil of 350 turns of number 16 wire (standard gauge).

Outstanding advantages of my improved system and power unit are that it enables the production, from a low potential direct current source, of a high voltage alternating current of a character which is able to illuminate gaseous signs such as neon light signs with substantial 35 uniformity and absence of flicker, thus overcoming the most noticeable disadvantages characterizing the illumination of such signs by induction coil systems. In addition I have found by the installations above noted that the current 40 output obtained by my method is of a character which does not produce any appreciable heating 45 of the tube itself, and thereby permits its usage under almost all sorts of weather conditions.

In the light of the foregoing disclosure it will 50 be perceived by those skilled in the art that various 55 out and sundry changes may be made, and various expedients resorted to, for applying the fundamentals of the power converting method and arrangement, power converting unit, method of illuminating gaseous tubes, and other phases of my invention, in various embodiments, and that the disclosed embodiment is to be construed as 60 illustrative, and not restrictive, of my invention.

I claim as my invention:

60 1. The method of illuminating a lamp of the neon-gas tube-type substantially equally throughout its length, and without objectionable flicker, which comprises the steps of drawing a current from a low potential source, dividing the current into two portions, passing one of said portions through the coil of an electromagnet, utilizing the magnetic force developed by said electromagnet to rapidly and repeatedly interrupt the entire current drawn from the source 65 with such rapidity as to avoid flicker and with

such ratio of "make" to "break" that the illuminating current derived by the method has the opposite sides of its cycle substantially equal, and passing the other portion of the current in parallel with the first portion through the primary of a step-up transformer and utilizing the magnetic flux developed by the said other part of said current solely for operation of said step-up transformer to produce a current of high voltage and of an alternating character with the opposite sides of its cycle sufficiently equal to illuminate said lamp substantially equally throughout its length. 10

2. A system for producing, from a low potential source of current, a current of high voltage 15 and of an alternating character with the opposite sides of its cycle sufficiently equal to illuminate a lamp of the neon-gas tube type substantially equally throughout its length, and further of a character to illuminate a lamp of said type 20 without objectionable flicker, which comprises a step-up transformer, a separate electromagnet in parallel with the primary of said step-up transformer, a series circuit for connecting said parallel circuits with the low potential source 25 of power, and vibrator contact means in said series circuits directly vibrated by energization and deenergization of said separate electromagnet to rapidly break and make said series circuit, said vibrator contact means being so tensioned that the speed and ratio of "make" to "break" produces the defined current output 30 from said transformer.

3. A system of the character defined in claim 2, having a large capacity non-electrolytic condenser in parallel with said contact means.

4. A converter of the class described comprising a transformer and an electromagnetic interrupter having its coil forming a parallel system with the primary of said transformer and 40 its interrupter contacts in series with said parallel system, said interrupter formed and adjusted to produce a ratio of "make" to "break" rendering the opposite sides of the cycle of the alternating current output of the transformer 45 substantially equal.

5. The method of obtaining a high-potential alternating current which comprises the steps of drawing a current from a low potential direct current source, dividing the current into two portions, passing one of said portions through a first circuit and utilizing it to produce electromagnetic flux, utilizing the electromagnetic flux to interrupt the entire current drawn from the source to thus terminate the creation of said flux, reestablishing the said entire current when creation of said flux is terminated, passing the other portion of said divided interrupted current through a second circuit in parallel with the first circuit, utilizing the current flowing in said second circuit to produce a fluctuating magnetic flux, utilizing the fluctuating flux produced by the current in said second circuit to induce a high potential alternating-current in an output circuit, establishing a high rate of interruption of the current drawn from the low-potential source, and establishing a ratio of "make" to "break" producing a current output having the opposite sides of its cycle substantially equal. 55 60 65
